UNITED STATES PATENT OFFICE.

WALTER E. PALMER, OF CICERO, ILLINOIS.

TABULATOR-STOP-SETTING DEVICE.

1,008,053.

Specification of Letters Patent.

Patented Nov. 7, 1911.

Application filed December 22, 1910. Serial No. 598,802.

REISSUED

To all whom it may concern:

Be it known that I, WALTER E. PALMER, a citizen of the United States, and a resident of Cicero, in the county of Cook and State of Illinois, have invented certain new and useful Improvements in Tabulator-Stop-Setting Devices; and I do hereby declare that the following is a full, clear, and exact description thereof, reference being had to the accompanying drawings, and to the characters of reference marked thereon, which form a part of this specification.

This invention relates to improvements in tabulating mechanism for typewriting machines and refers more specifically to novel means for setting and resetting the column or tabulator stops of such mechanism by which the carriage is arrested at predetermined points in its travel for printing a series of items in vertical columns. Tabulating mechanisms of this character usually embrace, in combination with the carriage and the machine frame, a series of stops supported on one of the parts and longitudinally adjustable with respect to the path of the carriage travel, and a coöperating device carried by the other part adapted, by manipulation of a key or like device, to be shifted into the path of one of the stops, the said key usually operating at the same time to release the carriage from the control of its letter spacing mechanism so as to permit the carriage to move under the influence of its actuating spring to a point or points determined by the adjustment of the stop or stops.

I have herein shown my invention as applied to the Oliver typewriter of the general construction illustrated in the prior patent to Knapp and Harting, No. 916,720, dated March 30th, 1909, but it will be understood that the essential features of the invention may be applied to other types of machines, and the invention is not, therefore, limited to the specific adaptation herein disclosed, except as to such claims wherein the particular structure is specifically set forth.

As shown in the drawings,—Figure 1 is a transverse section of the paper carriage and a portion of the shifting carriage. Fig. 2 is a fragmentary plan view of the stop setting device embracing my invention. Fig. 3 is a fragmentary rear elevation of the parts shown in Fig. 2. Fig. 4 is a face or front view of the paper carriage showing the adjustable tabulator stops thereon. Fig.

5 is a fragmentary view illustrating one of the stops and its supporting ratchet bar, showing the stop released from its supporting member. Fig. 6 is a fragmentary view illustrating the essential features of my invention, in a position different from that shown in Fig. 1. Fig. 7 is a view of the parts shown in Fig. 6, in still another position which they assume during operation.

As shown in said drawings, 10 designates the longitudinal frame member of the carriage, on the forward margin of which is formed the rack 11 which engages with the pinion 12 of the letter spacing mechanism, 70 said carriage being supported on and traveling on the rails 14 and 15 of the carriage shifting frame. The said frame member 10 is provided with a depending flange or bar 17 located just in rear of the vertical plane 75 of the rack 11. The bar 17 is provided at its lower margin with a plurality of closely spaced ratchet teeth 18, and is provided also on its front face with a scale marked to correspond with the letter space scale of the 80 carriage, and with the ratchet teeth 18. Mounted on said bar 17 are a plurality of adjustable tabulator or column stops 20 of the form shown best in Figs. 5, 6 and 7; each stop comprising parallel front and rear 85 members connected by the lower transverse member, and arranged to embrace the lower toothed margin of the bar 17. The front member of the stop is provided at its upper end near one margin with a stud 21 adapted to engage in a longitudinal groove 22 formed in and extending longitudinally of the bar 17, whereby said stops may be shifted longitudinally of the bar. The transverse members of said stops are provided 90 with holding teeth 23 adapted to engage the ratchet teeth 18 of the bar 17 to lock said stops in adjusted positions on the flange. The said stops are normally held in positions to engage the holding teeth 23 with 95 the ratchet teeth 18 of the bar 17 by means of the springs 25 attached to the stops and to the flange in the manner shown in the aforesaid patent to Knapp and Harting, No. 916,720, this being the normal position 100 of the stops. When the stops are swung downwardly about their pivot studs 21 to the position shown in Figs. 5 and 7 the stops are free to slide longitudinally of the ratchet bar 17, so as to be set in any desired 110 position along the bar; and when the stops are unrestrained the said springs 25 return

the stops to normal positions with the teeth 23 thereof engaged with the ratchet teeth 18 of the bar 17, whereby to lock the stops in adjusted positions. Said stops coöperate 5 with a key actuated stop member 27 pivotally mounted on the shift frame, said stop member being movable vertically into and, out of the path of the stops 20. Said stop member is shown as formed on the rear end 10 of the key actuated lever 28 which is pivotally mounted on a suitable bracket carried by the carriage shift frame. The lever 28 is provided with an upwardly and rearwardly extending arm 29 which is connected 15 by a horizontally arranged link 30 with the upper end of the shaft 31 that carries the pinion 12 of the letter spacing mechanism; the arrangement being such that when the lever 28 is swung to move the stop member 20 27 into the path of the stops 20, said pinion will be released from the rack of the letter spacing mechanism so that the carriage will be free to move under the influence of its actuating spring to a position determined 25 by the adjustment of the next adjacent stop 20. These features of the tabulating mechanism described are like that of the construction of the Knapp and Harting patent before referred to and constitute, in themselves, no part of the present invention. 30 Heretofore in tabulating mechanisms of this general type it has been necessary, when it is desired to adjust or reset the stops, as the stops 20, on their supporting member, to effect such adjustment by direct manual engagement, either when the carriage is in place on the machine frame or when the carriage has been removed from the machine frame to give freer access to the stops. 35 Where a great variety of work is done, as, for example, in large offices requiring tabulating in columns of different widths, such readjustment or resetting of the stops to change the spacing of the columns is tedious 40 and consumes considerable time. 45

It is the object of the present invention to provide means which may be operated by a single actuating key or like device to set or adjust a plurality of stops to vary the spacing of the tabulated work without removing the carriage or manually shifting the stops, and a further object of this invention is to separately reset any one of a plurality of stops, as the stops 20, by a single 55 actuating device.

In the present Oliver construction it is convenient to associate the setting or adjusting device with, or mount the same on the right hand margin release key lever 32, 60 by which to release the stop member 33, carried by the rear end of said key lever, from or move it out of the path of the right hand margin stop 34 which is also adjustably mounted on the ratchet bar 17, as 65 shown in Fig. 4. While this arrangement

of the setting or adjusting device is desirable to apply my tabulator stop setting or adjusting device to a machine of the kind shown without material change in the construction thereof, yet it is to be understood 70 that the invention in its broader aspect is not limited to this arrangement, but said setting or adjusting device may be provided with a separate actuating key. The said setting or adjusting device comprises, in 75 general terms, a rearwardly directed finger 36 which is made rigid with and extends rearwardly from a swinging member 37 that is pivoted at its upper end by a pivot pin 38 to a fixed part 39 of the carriage shift frame. The said finger 36 extends rearwardly beneath the rack 11 of the letter spacing mechanism and into the upper part 80 of the groove 22 which receives the pivot studs 21 of the stops 20; the said groove 85 being shown as somewhat enlarged by cutting away the metal of the bar 17 in order to receive said finger and to permit the carriage to be moved freely without restricting engagement of the finger with the carriage frame or said stops. The said swinging member 37 is provided at one side with a laterally extending pin 41 which normally lies a distance above the upper margin of the key lever 32, and is adapted, when the 90 rear end of the key lever is swung upwardly, to be engaged by the latter (as shown in Fig. 6). In the continued swinging movement of the key lever the contact of the lever with said pin 41 serves to swing 95 the member 37 forwardly, and thereby swing the rear end of the finger 36 downwardly. The said stops are provided at their upper ends, and near the margins thereof remote from the pivot studs 21, with 100 upwardly opening notches 42, and the relation of the stop member 27 with the rear end of the finger 36 is such that when the carriage is arrested by engagement of one 105 of the stops 20 with said stop member 27 the rear end of the said finger 36 will be located directly over the notch 42 of the adjacent stop, as indicated at the left hand end of Fig. 4. Therefore, when the carriage 110 is thus arrested by engagement of one of the stops 20 with the stop member 27 and it is found necessary or desirable to reset or adjust the stop to bring the column to the proper position on the paper receiving the printed impressions, the key lever is depressed, as shown in Figs. 5 and 6, and said lever engages the pin 41 to swing the member 37 forwardly and thereby swing the rear end of the finger 36 downwardly into engagement with the notch 42 of the adjacent 115 stop to swing the stop on its pivot stud to the released position indicated in Fig. 5. The stop may be held in this position by said finger and the carriage shifted in one direction or the other, either by hand, or by the 120 125 130

forward or back-spacing mechanism, and thereby change the relative position of the stop on its carrying member or bar 17 so as to adjust or set said stop to arrest the carriage at a new point for tabulating work. It will be readily seen that either of the stops 20 may thus be adjusted or reset, and that such resetting operation is effected by a single manually operable device, as the key lever 32.

When the setting or adjusting device is mounted on or associated with the right hand marginal release key, and is therefore located over the stop member 33 of said key, the said stop member may be provided with the upwardly opening notch 44 to receive the finger 36 when swung downwardly into engagement with the notched stop 20 and thus stiffen said finger against lateral deflection, as will be evident. In other adaptations of the setting finger it may be otherwise stiffened.

While I have herein shown one practical embodiment of my invention for resetting the column or tabulating stops of tabulating mechanisms, it will be understood that the invention is not limited to the construction herein shown, but is applicable to all tabulating mechanism of this general character, embracing a plurality of stops adapted to be longitudinally adjusted on their support, and to be engaged by a co-acting stop device or member which is arranged to be shifted into and out of the path of the adjustable stops.

I claim as my invention:—

1. In a tabulator mechanism for typewriting machines, the combination with a plurality of tabulator stops and the supporting member along which they are longitudinally spaced and upon which they are mounted to be adjusted toward and from each other, of a single movably mounted setting or adjusting device adapted to directly engage and separately release and set or adjust the stops along their supporting member.

2. In a tabulator mechanism for typewriting machines, the combination with a plurality of tabulator stops and a supporting member therefor, along which the stops are longitudinally spaced and upon which they are adapted to be adjusted toward and from each other, with means for locking the stops in adjusted positions, of a movably mounted setting device adapted to separately and independently release the locking mechanism of each stop, and hold the stop to permit it to be adjusted by relative movement of the supporting member.

3. In a tabulator mechanism for typewriting machines, the combination with a plurality of tabulator stops and a supporting member therefor along which the stops are adapted to be adjusted, with means for locking the stops in adjusted positions, of a lever

operated setting finger adapted to release the locking means and to confine the stops while relative adjustment of the stops and bar is effected.

4. In a tabulator mechanism for typewriting machines, the combination with a plurality of tabulator stops and a supporting bar along which said stops are adapted to be adjusted, said stops having rocking motion on the bar whereby they may be locked to and released from the bar, and means to interlock with the stops to rock them to releasing positions and to retain or confine the stops while being adjusted on said bar.

5. In a tabulator mechanism for typewriting machines, the combination with a member carried by or movable with the carriage and a plurality of stops having means to lock them on said member and adapted to be adjusted longitudinally of the member, of means carried by a relatively fixed part of the machine for separately engaging the stops to release them from said member and to hold the stops while the member is shifted to adjust the stops on said bar.

6. In a tabulator mechanism for typewriting machines, the combination with a member carried by or movable with the carriage and a plurality of stops having means to lock them on said member and adapted to be adjusted longitudinally of the member, of a lever actuated finger pivoted to a relatively fixed part of the frame and adapted to interlock with the stops to release them from the member and to hold them while said member is being longitudinally shifted to thereby adjust the stops on the member.

7. In a tabulator mechanism for typewriting machines, the combination with a member carried by or movable with the carriage and a plurality of stops having means to lock them on said member and adapted to be adjusted longitudinally of the member, of a lever actuated finger pivoted to a relatively fixed part of the frame and adapted to interlock with the stops to release them from the member and to hold them while said member is being longitudinally shifted to thereby adjust the stops on the member, and means arranged to brace or stiffen the finger near its free end.

8. A tabulator stop setting device comprising a lever actuated member having means to separately engage the tabulator stops to release the latter from their supporting member and confine the stops while they are being adjusted on the support, and means for movably supporting the lever actuated member.

9. In a tabulator or stop mechanism for typewriting machines, the combination with a stop device and its supporting member to which the stop device is normally locked, of a single setting device adapted by movement thereof in one direction to interlock

with the stop device to hold it stationary and to release the stop device from its supporting member.

10. In a tabulator or stop mechanism for typewriting machines, the combination with a stop device and its supporting member to which the stop device is normally locked, of a pivoted lever arranged when swung in one direction to release the stop device from its supporting member and lock it stationary, and when swung in the other direction to relock the stop device to its supporting member and release said stop device.

11. A typewriting machine embracing an endwise traveling paper carriage and its supporting frame a bar carried by and arranged longitudinally of the carriage, a series of spaced tabulator stops on the bar and adjustable longitudinally therealong with means for locking them in adjusted position, means mounted on said frame to separately and independently release said stops from the bar and to hold them stationary while the carriage is shifted endwise and thereby reset the stops on said bar, and a cooperating stop on the frame.

12. A typewriting machine embracing an endwise traveling carriage and its supporting frame, a bar carried by and arranged longitudinally of the carriage and provided with a series of closely spaced notches, a series of tabulator stops spaced longitudinally of said bar and slidable endwise thereof and provided with means to engage the notches of the bar to lock the stops thereto, means carried by said frame arranged to separately release said stops from the notches of said bar and to hold them stationary while the carriage is shifted endwise to thereby reset the stops on the bar and a cooperating stop on the frame.

13. A typewriting machine embracing an endwise traveling carriage and its supporting frame, a bar carried by and arranged longitudinally of the carriage and provided with a series of closely spaced notches, a

series of tabulator stops spaced longitudinally of said bar and slidable endwise thereof, and having a rocking or tilting movement thereon to engage the stops with and release them from the notched bar, means carried by the frame for so releasing the stops from said bar and for holding them temporarily fixed during the endwise movement of the carriage and a coöperating stop carried by said frame.

14. A typewriting machine embracing an endwise traveling carriage and its supporting frame, a letter spacing mechanism embracing a rack on the carriage and a pinion and a tabulator mechanism embracing a flange on the rack bar, a series of longitudinally spaced tabulator stops carried by and adjusted longitudinally of said flange, a co-operating stop on the carriage and resetting means embracing a member mounted on the frame to separately engage the tabulator stops and release them from the said flange and to hold them fixed while the carriage is shifted endwise.

15. In a typewriter, an endwise traveling carriage and its supporting frame, a series of tabulator stops carried by and adjustable relatively to each other longitudinally of the carriage, and having means to lock them in adjusted position, a coöperating stop on the frame, a right hand margin stop on the carriage, a coöperating stop therefor on the frame having a release key, and means operable by movement of the said release key to release the tabulator stops from the carriage and to hold them while the carriage is shifted to thereby adjust the tabulator stops on the carriage.

In testimony, that I claim the foregoing as my invention I affix my signature in the presence of two witnesses, this 16th day of December A. D. 1910.

WALTER E. PALMER.
